United States Patent Office

Des. 215,752
Patented Oct. 28, 1969

215,752

CIGARETTE LIGHTER

Takeshi Mizutani, Tokyo, Japan, assignor to Kanamaru
Shoten, Ltd., Tokyo, Japan

Filed June 3, 1968, Ser. No. 12,188

Term of patent 14 years

Claims priority, application Japan Apr. 22, 1968

Int. Cl. D27—05

U.S. Cl. D48—27

FIG. 1

FIG. 3

FIG. 2

FIG. 4

FIG. 6

FIG. 5

FIG. 7

FIG. 8

FIG. 1 is a perspective view of the lighter embodying the present design;

FIG. 2 is a side view thereof with top closed;

FIG. 3 is a back view thereof with top closed;

FIG. 4 is a front view thereof with top closed;

FIG. 5 is a side view thereof with top open;

FIG. 6 is a top view thereof with top open;

FIG. 7 is a front view thereof with top open; and

FIG. 8 is a bottom view thereof with top open.

The characteristic features of my design reside in the windguard and related elements on the top of the lighter body as best shown in FIGS. 1 and 5.

I claim:

The ornamental design for a cigarette lighter, as shown and described.
